UNITED STATES PATENT OFFICE.

HENRY I. COHEN, OF MINNEAPOLIS, MINNESOTA, ASSIGNOR TO LIBERTY STAR COMPANY, OF MINNEAPOLIS, MINNESOTA, A COPARTNERSHIP CONSISTING OF HENRY I. COHEN AND LEO SHAPIRO.

DESIGN FOR AN EMBLEM OR BADGE.

5,340.

Specification for Design.

Patented Oct. 5, 1920.

Application filed August 15, 1918. Serial No. 250,083. Term of patent 3½ years.

To all whom it may concern:

Be it known that I, HENRY I. COHEN, a citizen of the United States, residing at Minneapolis, in the county of Hennepin and State of Minnesota, have invented a new, original, and ornamental Design for an Emblem or Badge, of which the following is a specification, reference being had to the accompanying drawing, forming part thereof.

The figure is a plan view of an emblem or badge showing my new design.

I claim:

The ornamental design for an emblem or badge, as shown.

HENRY I. COHEN.
